UNITED STATES PATENT OFFICE.

FRANKLIN P. EASTMAN, OF NEW YORK, N. Y.

DUMPING-SCOW.

SPECIFICATION forming part of Letters Patent No. 629,554, dated July 25, 1899.

Application filed August 9, 1898. Serial No. 688,223. (No model.)

To all whom it may concern:

Be it known that I, FRANKLIN P. EASTMAN, of the city of New York, borough of Manhattan, in the county and State of New York, have invented a new and Improved Dumping-Scow, of which the following is a full, clear, and exact description.

The invention relates to dumping-scows, such as shown and described in the Letters Patent of the United States No. 359,012, granted to me on March 8, 1887.

The object of the present invention is to provide a new and improved dumping-scow arranged to facilitate the dumping of all kinds of material, especially house and street refuse and the like.

The invention consists of novel features and parts and combinations of the same, as will be fully described hereinafter and then pointed out in the claims.

Reference is to be had to the accompanying drawings, forming a part of this specification, in which similar characters of reference indicate corresponding parts in all the figures.

Figure 1 is a plan view of the improvement with parts broken out. Fig. 2 is a side elevation of the same with parts broken out and parts in section. Fig. 3 is an enlarged transverse section of the improvement on the line 3 3 in Fig. 1. Fig. 4 is an enlarged face view of part of the improvement, showing the locking device for the side; and Fig. 5 is a transverse section of the same on the line 5 5 in Fig. 4.

The improved dumping-scow is provided with a suitably-constructed framework A, to which are attached the bottom B and the inclined floors C, forming a peak-shaped section extending centrally and longitudinally from one end D of the scow to the other end D', as is plainly indicated in Figs. 1 and 2. One or more bulkheads E may be arranged on the side of the scow to give the desired strength to the structure.

On the lower outer end of each floor C are arranged pivots F, on which are hung arms G, normally extending vertically to support at their upper outwardly-curved ends the sides H, extending from one end D to the other, so as to form with the ends and the inclined floors compartments on each side of the scow. The connection between the arms

G and the sides H is by means of pivots, so that when the arms G are swung outward, as indicated in dotted lines in Fig. 3, then the sides H move with the arms and hang vertically therefrom, owing to their weight, to permit the contents of the scow to slide down the inclined bottom C into the surrounding water.

In order to keep the sides H and arms G in a vertical or closed position, as illustrated in full lines in Fig. 3, I connect the sides with a pair of transversely-extending ropes or chains I, extending through openings in the floor C to the inside of the framework and passing over fixed bearings or guides J to then connect with a longitudinally-extending rope or chain I', attached to the piston-rod of a hydraulic or other ram K of any approved construction and located at or near one end of the scow. When the piston of the ram is in an outermost position, the sides H are closed, and when the motive power for the ram is permitted to escape therefrom then the sides H and the arms G are free to swing outward by the pressure of the load resting against the said sides H.

In order to lock the free or lower ends of the sides H in place while loading the scow and transporting it to a place of discharge, I provide locking devices L, each comprising a hook L', fulcrumed on the lower end of the corresponding floor C and adapted to be engaged by a locking-plate L², having an elongated aperture through which is adapted to pass the outer end of the hook. The locking-plate L² is fitted to slide vertically in suitable bearings L³, (see Figs. 4 and 5,) attached to the corresponding side H, and the said plate is hung on a rope L⁴, extending upwardly and passing over a pulley L⁵. The several ropes L⁴ for both sides connect with a rope L⁶, leading to a capstan, windlass, or other similar winding apparatus for winding up or unwinding the rope or chain L⁶ to raise or lower the several plates L² simultaneously. The hook L' of each locking device also extends through an opening in the corresponding side H and is adapted to normally rest on a projection L⁷, attached to the corresponding floor C. When the side H is in an open position, the hook L' rests on the projection L⁷, and when the arms G swing inward and carry the side along then

the hook passes through the opening in the side and that of the locking-plate L², and when the side has reached its innermost position then the rope L⁶ is wound up on the windlass or capstan N, so as to draw the plate L² upward and swing the hook L' into a locking position to securely fasten the free end of the side in place. Now it is evident that when the sides are closed the scow can be readily loaded with house and street refuse and the like and then towed to the place of dumping, and when the place is reached the operator unlocks the sides H by reversing the windlass N to allow the rope L⁶ to unwind and the plates L² to drop and disconnect the hooks L' from the sides H. The sides H are now free to swing outward with the arms G as a fulcrum, and the operator now permits the motive agent in the ram K to discharge, so that the arms G are free to swing outward, carrying the sides H with them into the position indicated in dotted lines in Fig. 3, so that the contents of the scow can readily slide down the inclined floor C into the surrounding water. By the arrangement described no obstruction in any shape or form is left for the refuse to cling to after the sides H are opened, so that a complete discharge of the entire load takes place.

It is understood that house and street refuse when loaded, for instance, on a scow of the construction shown and described in the patent above referred to is liable to cling to the longitudinal rails, which are entirely dispensed with in the present construction. It will further be seen that the load is discharged simultaneously from both sides of the scow, as the sides open at the same time.

Having thus fully described my invention, I claim as new and desire to secure by Letters Patent—

1. A dumping-scow, provided with movable

sides, and arms on which the sides are hung, said arms being pivoted to the scow, substantially as shown and described.

2. A dumping-scow, provided with movable sides, arms on which the sides are hung, said arms being pivoted to the scow, and a locking device for locking the sides in place on the scow, substantially as shown and described. 45 50

3. A dumping-scow provided with an inclined floor, arms pivoted at or near the lower, outer ends thereof, and a side hung on the upper ends of the said arms and adapted to form a compartment with the floor and the ends of the scow when closed, substantially 55 as shown and described.

4. A dumping-scow provided with an inclined floor, arms pivoted at or near the lower, outer ends thereof, a side hung on the upper 60 ends of the said arms and adapted to form a compartment with the floor and the ends of the scow when closed, and means for permitting a swinging motion to the said arms to allow the sides to open or close, substantially 65 as shown and described.

5. A dumping-scow provided with an inclined floor, arms pivoted at or near the lower, outer ends thereof, a side hung on the upper 70 ends of the said arms and adapted to form a compartment with the floor and the ends of the scow when closed, means for permitting a swinging motion to the said arms to allow the sides to open or close, and a locking device under the control of the operator, for 75 fastening the lower, free end of the side to the scow at the lower outer end of the corresponding floor thereof, substantially as shown and described.

FRANKLIN P. EASTMAN.
